Primary Examiner — Keith J Wilson*Assistant Examiner* — Carolyn W Davis(74) *Attorney, Agent, or Firm* — Jeenam Park(57) **CLAIM**

The ornamental design for a range hood, as shown and described.

DESCRIPTION

FIG. 1 is a perspective view of a range hood, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

The broken lines illustrate portions of the range hood and forms no part of the claimed design.

1 Claim, 8 Drawing Sheets(56)
